FAN APPARATUS

Sam F. Shawhan, Syracuse, N. Y., assignor to
 Carrier Corporation, Syracuse, N. Y., a corporation of Delaware

Application June 4, 1938, Serial No. 211,795

4 Claims. (Cl. 230—114)

This invention relates to air circulating apparatus, and more particularly to blower apparatus of the housed or centrifugal type.

- The general object of the present invention is to provide an improved blower apparatus which is considerably more quiet in operation than apparatus of the same general class heretofore available, and which requires less power than such apparatus.
- 10 Another object of the invention is to provide a fan unit embodying novel means for insuring relatively quiet operation of the unit, and for appreciably reducing the required power input to such unit.

15 Another object of the invention is to provide a fan structure which is simple in design and practically no more expensive to build than conventional fan structures, but which affords marked operating advantages and economies.

20 Another object of the invention is to provide a fan unit comprising one or more centrifugal fans with means for reducing the operating noise level and increasing the operating efficiency of such unit.

25 Broadly, the invention contemplates reducing the loss which usually occurs as the air to be circulated enters the fan intakes. The eddying and similar actions which occur at such points result in a major portion of the noise generated by operation of the fan, and the energy thus lost requires a corresponding increase in the power supplied for driving the fan.

30 A feature of the present invention resides in substantially reducing such losses, by directing the air delivered to the inlet openings of the fans in a direction corresponding to the direction of rotation of the fan rotors. Thus the air is taken within the fans with a minimum of power loss and noise.

35 Another feature of the invention resides in providing a casing having one or more centrifugal fans therein, each of said fans having single or double inlet openings, means for delivering air to the casing interior, and means within said casing for routing said air, before it is delivered to said inlet openings, in a direction corresponding to the direction of rotation of the rotors of said fans, so that the air enters the fans smoothly, easily and with relatively little noise, by avoiding sudden change in the direction of flow of air entering the fan inlets.

40 Still another feature of the invention resides in delivering air to a casing having one or more centrifugal fans therein, and imparting to said air, before it is delivered to said fans, a rotary

motion in the same direction as that in which the rotors of said fans are rotated.

Another feature of the invention resides in carrying out the operation set forth in the preceding paragraph by the provision of suitably designed air-directing baffles positioned within said casing.

Other objects and features of the invention will be more clearly apparent from the following description, to be read in connection with the accompanying drawings, in which

Fig. 1 diagrammatically illustrates a sectional view of an improved fan apparatus embodying the invention;

Fig. 2 diagrammatically illustrates a front elevational view of the apparatus of Fig. 1;

Fig. 3 diagrammatically illustrates, in a view similar to that of Fig. 1, an alternative form of the invention;

Fig. 4 is a view similar to that of Fig. 3, illustrating another embodiment of the invention;

Fig. 5 diagrammatically illustrates another alternative embodiment of the invention;

Fig. 6 diagrammatically represents an embodiment of the invention in which adjustable baffles are employed; and

Fig. 7 diagrammatically represents another alternative form of the invention.

Referring now to the drawings, similar designations referring to the same or similar parts, the numeral 10 designates a casing housing one or more fans of the centrifugal type. As illustrated, casing 10 contains two fans of this type, each comprising a rotor 11 and a conventional discharge scroll 12. The rotors 11 are preferably mounted upon and driven by a common shaft 13, suitably journalled as at 14, and actuated by any suitable driving means. As illustrated, motor 15 drives shaft 13 through belt 16.

In the embodiment of the invention illustrated in Figs. 1 and 2, air is delivered to the casing 10 through one or more inlet openings 18 formed in the rear wall thereof. Preferably, inlet opening 18 is provided with a flange 19, to facilitate the connection of casing 10 to a duct or the like (not shown) which may be used for supplying air to the unit. Similarly, the casing is provided with outlet openings 20, one of such openings being provided in registry with the outlet end of each fan discharge scroll 12. Outlet openings 20 are preferably provided with flanges 21, similar to flanges 19, for the connection of suitable air discharge ducts.

Each fan scroll 12 is provided with inlet openings 22, through which air enters to the fan rotors

11. As shown for purposes of illustration, the fans are of the double inlet type.

The fan rotors 11 are rotated in counterclockwise direction, as viewed in Fig. 1.

- 5 12. In order to reduce the intake air losses and to reduce the power requirements of the apparatus, there is provided a baffle 23, proximate the top of the inlet opening 19 and extending lengthwise substantially throughout the length of casing 10.
- 10 13. Baffle 23 slopes downwardly, and extends to a point at or proximate the scroll 12. The effect of baffle 23 is to route air intaken through inlet 19 downwardly within casing 10 in the direction indicated by arrows 24. This tends to establish a 15 rotary circulation of air in casing 10 in the same direction as that in which rotors 11 are rotated. Accordingly, the air intaken within the openings 22 from this rotary circulation passes into the fan rotor without any sudden change in direction and 20 with a minimum of shock, energy loss and noise. Further to facilitate the rotary circulation of air within the casing 10, there may be provided baffle 25, preferably extending throughout the length of casing 10. Baffle 25 extends upwardly and to 25 the right from a point at the bottom of the casing 10 and between the front and rear thereof. Provision of baffle 25 serves to eliminate eddying in the lower front corner of casing 10, and hence while this baffle is not indispensable, it is preferably provided.

In Fig. 3 is illustrated a modification of the invention in which an alternative baffle formation is utilized, the structure of Fig. 3 and Fig. 2 being otherwise substantially the same. In Fig. 35 3, baffle member 26, extending substantially completely throughout the length of casing 10, and extending downwardly from the top of casing 10, roughly approximates in shape the outline of the fan scroll 12. As in the case of baffle 23 of Fig. 1, 40 baffle 26 deflects downwardly the air entering the casing 10 and thus initiates a rotary circulation of air within the casing in the same direction as that of the rotors 11. The baffle 26 preferably extends downwardly to a point proximate the center 45 of the fan inlet openings 22, but the baffle may be somewhat shallower than this if desired, since the downward sweep of air deflected thereby will prevent any appreciable quantity of air from entering the upper portion of the inlet openings in a direction counter to that of the fan rotors 11.

50 It will be understood that the invention is not limited to any particular shape or depth of baffle, and that any baffle positioned in the path of air intaken within the casing and serving to prevent the direct entry of air into the fan rotors in a direction counter thereto and also serving to initiate a circulation of intaken air in the same direction as that of the fan rotors, is within the purview of the invention.

60 In Fig. 4 is illustrated a fan structure in which the air inlet, here designated 18a, is provided at the bottom, rather than at the rear of casing 10. A flange 19 is preferably provided, as in the case of Figs. 1 and 3. In order to initiate desired rotary circulation of air in the casing in the same direction as that of the fan rotors, a baffle 27 is provided, preferably throughout the entire length of the casing 10. Baffle 27 extends upwardly and to the front from the rear end of inlet opening 18a, and is preferably concavely curved. Baffle 27 prevents air from directly entering the rearward portion of the openings 22 in a direction counter to that taken by the blades of rotor 11, and causes such air as enters the casing 10 to be circulated 75 in a rotary motion before it is admitted to the fan

inlet openings. Baffle 25 is shown, but as set forth above, may be dispensed with if desired.

Fig. 5 represents another modified form of the invention in which the air enters casing 10 through opening or openings 18 at the rear of the casing and is discharged through openings 20a at the top thereof. In this case the rotor 11a is rotated in clockwise direction within scroll 12a. To accomplish the aims hereinbefore explained, there is provided a baffle 28, extending substantially 10 completely throughout the length of casing 10, and extending upwardly and toward the front of the casing from the bottom of inlet opening 18. Baffle 28 corresponds in all substantial respects to baffles 23, 26 and 27, of the preceding figures. Further to this end, there may be provided, if desired, an auxiliary baffle 29, corresponding to baffle 25. As explained in connection with baffle 25, baffle 29 may be dispensed with if desired.

20 Fig. 6 illustrates an arrangement in which casing 30, containing fan scroll 12a and fan rotor 11a rotating in clockwise direction as indicated by the arrow, is provided with an air inlet opening 31 in one side thereof and another air inlet opening 32 in the opposite side thereof. At the inlet opening 31 and extending within the casing are a plurality of stationary baffles 33 adapted to deflect upwardly within the casing 30 air received through the air inlet 31. Pivoted at a point below the baffles 33, as at 34, is a baffle 35 having a 30 flanged end portion 36. When damper 35 is in the position indicated, air intaken within the casing is routed in the direction indicated by the arrows so that the desired rotary circulation of air within the casing above described is established. When it is desired to reduce the volume of air intaken within the inlet 31, the damper 35 may be moved further toward the ends of baffles 33. If it is desired completely to stop air flow through inlet 31 the damper 35 may be swung so that its 40 flanged portion 36 overlies flange member 37 extending from the side of the casing 30 just above the air inlet 31.

35 The volume of air admitted through air inlet 32 may be controlled as by damper 38 pivoted at 45 a point proximate the bottom of air inlet 32, as indicated at 39. When the damper is in relatively open position it will be seen that the air intaken through inlet 32 flows in the desired direction, as may be further insured by the provision of stationary louvers 40. When the damper 38 is swung upwardly somewhat to restrict air flow through inlet 32, the tendency is for the air to shoot upwardly within the casing, and to overcome this tendency, in order to provide the desired rotary 55 circulation in the same direction as that of the rotor, there may be provided a baffle 41. Thus, although the proportions of air intaken through inlets 31 and 32 may be varied at will, by adjusting the positions of the dampers 35 and 38 in any 60 desired manner, the desired rotary circulation of air within the casing is maintained at all times.

Fig. 7 illustrates an alternative arrangement in which casing 42 contains a scroll 12b and a rotor 11b rotated in clockwise direction. The casing 42 65 is provided with a discharge opening 20b in registry with the discharge scroll 12b. An air inlet opening 18b is formed in the bottom of the casing and is preferably provided with a flange 19b for connection of a suitable duct thereto. Proximate 70 the right-hand side of the casing and at a level proximate or below that of the fan scroll, there is provided a baffle 43 extending downwardly toward the left-hand portion of the casing. Baffle 43 has the effect of routing air intaken through 75

the right-hand portion of inlet 18b in the direction indicated by the arrows. Baffle 43 thus prevents entry of air from the inlet 18b to the inlet of fan rotor 11b in a direction counter to the rotational direction of rotor 11b. Baffle 43 initiates rotary circulation of air within the casing 42 which enables such air to be intaken within the fan quietly and with little power loss. Baffle 43 may be curved somewhat as indicated. It is preferred to make the baffle 43 of substantial width, in order to utilize fully the advantages of such an arrangement. Although a short baffle does not physically separate the entire right-hand portion of the fan inlet from the air inlet 18b, the deflection of air caused by the baffle is sufficient to initiate the rotary circulation of air within the casing 42 and thus to provide the desired results.

In the interests of conciseness and brevity, the drawings and description have been limited to certain illustrative forms of the invention, which is to be understood as embracing various embodiments not specifically illustrated or described. For example, the arrangement of Fig. 1 might be modified by a reversal of various elements thereof. Thus, the air inlet to the casing, instead of being in the rear of the casing might be formed at the front thereof and the fan might be similarly turned about so that the discharge outlet is toward the rear of the casing rather than toward the front thereof, the direction of rotation of the rotor in such case then being clockwise rather than counterclockwise. The baffle 23 would then be positioned at the front of the casing sloping downwardly and toward the rear thereof. Such rearrangement of the parts constitutes a mere reversal however, such arrangement being substantially the same as that illustrated in Fig. 1. The arrangements of the other figures might similarly be reversed.

Preferably, the various baffles which have been described extend substantially completely and continuously throughout the length of the casing.

Since these and many other changes may be made in the invention without departing from its scope, it is intended that all matter contained in the above description or shown in the accompanying drawings shall be interpreted as illustrative only and not in a limiting sense, applicant limiting himself only as indicated in the appended claims.

50 I claim:

1. In an apparatus of the character described, including a casing having blower means of the centrifugal type disposed therein, an air inlet formed in said casing, guide vane means disposed proximate said inlet opening and adapted to direct air intaken within said opening in a direction concurrent with the direction of rotation of said blower means, and an adjustable baffle positioned proximate the discharge end of said vane means and adapted to overlie the ends of said vane means and provided with a flange-like extension adapted to initiate rotary circulation within said casing of air discharged from said vane means.

65 2. In an apparatus of the character described, including a casing having blower means of the centrifugal type disposed therein, an air inlet formed in said casing, guide vane means disposed proximate said inlet opening and adapted to

direct air intaken within said opening in a direction concurrent with the direction of rotation of said blower means, an adjustable baffle positioned proximate the discharge end of said vane means and provided with a flange-like extension 5 adapted to initiate rotary circulation within said casing of air discharged from said vane means, a second air inlet opening formed in said casing and baffle means in combination with said second inlet opening for initiating rotary circulation 10 within said casing of air introduced through said second inlet opening, said first-mentioned baffle means and said second-mentioned baffle means being adapted variably to control the proportions of air introduced within said casing while insuring the maintenance of rotary circulation of air within the casing regardless of variations in the proportions of air introduced through the different inlet openings.

3. In an apparatus of the character described, 20 including a casing having blower means of the centrifugal type disposed therein, an air inlet formed in said casing, guide vane means disposed proximate said inlet opening and adapted to direct air intaken within said opening in a direction concurrent with the direction of rotation of said blower means, an adjustable baffle positioned proximate the discharge end of said vane means and adapted to initiate rotary circulation within 25 said casing of air discharged from said vane means, a second air inlet opening formed in said casing and baffle means in combination with said second inlet opening for initiating rotary circulation within said casing of air introduced through said second inlet opening, said first-mentioned baffle means and said second-mentioned baffle means being adapted variably to control the proportions of air introduced within 30 said casing while insuring the maintenance of rotary circulation of air within the casing regardless of variations in the proportions of air introduced through the different inlet openings.

4. In an apparatus of the character described, 40 including a casing having blower means of the centrifugal type disposed therein, an air inlet formed in said casing, guide vane means disposed proximate said inlet opening and adapted to direct air intaken within said opening in a direction concurrent with the direction of rotation of said blower means, an adjustable baffle positioned 45 proximate the discharge end of said vane means and adapted to initiate rotary circulation within said casing of air discharged from said vane means, a second air inlet opening formed in said casing and baffle means in combination with said second inlet opening for initiating rotary circulation within said casing of air introduced through said second inlet opening, said first-mentioned baffle means and said second-mentioned baffle means being adapted variably to 50 control the proportions of air introduced within said casing while insuring the maintenance of rotary circulation of air within the casing regardless of variations in the proportions of air introduced through the different inlet openings, said 55 first and second air inlet openings being formed in different parts of said casing and being arranged to deliver air within said casing in different directions.
